(57) **CLAIM**

The ornamental design for a front face of a display panel of an audio and video accessory for an electronic device, as shown and described.

DESCRIPTION

FIG. 1 is a front view of the front face of a display panel of an audio and video accessory for an electronic device according to the present invention.

FIG. 2 is a rear view of the front face of a display panel of an audio and video accessory for an electronic device of FIG. 1.

FIG. 3 is a left side view of the front face of a display panel of an audio and video accessory for an electronic device of FIG. 1.

FIG. 4 is a right side view of the front face of a display panel of an audio and video accessory for an electronic device of FIG. 1.

FIG. 5 is a top view of the front face of a display panel of an audio and video accessory for an electronic device of FIG. 1.

FIG. 6 is a bottom view of the front face of a display panel of an audio and video accessory for an electronic device of FIG. 1.

FIG. 7 is a top view of the front face of a display panel of an audio and video accessory for an electronic device of FIG. 1 with the display in a closed position; and,

FIG. 8 is a reduced front and left perspective view of front face of a display panel of an audio and video accessory for an electronic device according to the present invention.

Portions of the design shown in dashed lines form no part of the claimed invention.
